PLASTIC BOTTLE

Robert J. Musel and Harry N. Carpenter, Westerly, R. I., assignors to Plax Corporation, West Hartford, Conn., a corporation of Delaware

Application November 3, 1953, Serial No. 27,432

Term of patent 14 years

(Cl. D58—25)

To all whom it may concern:

Be it known that we, Robert J. Musel and Harry N. Carpenter, citizens of the United States, residing at Westerly, Rhode Island, have invented a new, original, and ornamental Design for a Plastic Bottle, of which the following is a specification, reference being had to the accompanying drawing, forming a part hereof.

Fig. 1 is a top plan view of a plastic bottle embodying our design; and

Fig. 2 is a side elevation view thereof, showing parts broken away for the purpose of convenience.

The dominant feature of our design resides in the portions shown in full lines.

We claim:

The ornamental design for a plastic bottle, as shown and described.
